UNITED STATES PATENT OFFICE

2,073,173

WINDSHIELD REGULATOR

Albert T. Potter, Detroit, Mich., assignor to Ainsworth Manufacturing Corporation, Detroit, Mich., a corporation of Michigan

Application May 3, 1934, Serial No. 723,650

3 Claims. (Cl. 268—119)

My invention relates to windows and particularly to a regulator employed in combination with a window for effecting its operation to open and closed positions.

Various types of regulators have been employed heretofore in the art for moving windows to various positions. Some are employed which move the windows to vertical open and closed positions while others are employed to move the window horizontally.

In practicing my invention, I employ a window regulator in combination with the window which swings the window on pivotal supports for ventilating purposes. The pivots or trunnions are disposed inwardly from the vertical edges of the glass so that a portion of the window swings outwardly of the frame as the remaining portion thereof moves inwardly and so disposed that both portions may be aligned with the frame to have the window sealed therein.

The operating device comprises a worm and worm wheel sector which is supported between two channel-shaped brackets having outwardly directed mated flanges and spaced web portions to form a rigid, yet simple construction. The worm has a recessed pivot which receives one of the trunnions and is provided with a locking strap by which the trunnion is rigidly secured, so that the regulator functions as a support as well as a pivot for the window.

Accordingly, the main objects of my invention are: to provide a window pivoted on trunnions one of which is secured to a device which actuates the window to open and closed positions; to provide an operating device for a pivoted window embodying a pair of worm elements which are encased between channel-shaped brackets embodying means for supporting the regulating device; to provide a regulating device with a worm and worm sector mounted in spaced channel-shaped elements, the upper portion of the sides and outwardly extending flanges of which are secured together to form a housing; to provide a recess in the worm sector shaft for receiving the end of the trunnion of the window and to rigidly secure the trunnion thereto; and, in general, to provide a regulating device which functions as the support and pivot for a window which is simple in construction, positive in operation and economical of manufacture.

Other objects and features of novelty of my invention will be either specifically pointed out or will become apparent when referring, for a better understanding of my invention, to the following

description taken in conjunction with the accompanying drawing, wherein:

Figure 1 is a broken view in elevation, with a part in section, of a window and frame and regulator embodying features of my invention, 5

Fig. 2 is an enlarged sectional view of the structure illustrated in Fig. 1, taken on the line 2—2 thereof,

Fig. 3 is an enlarged sectional view of the structure illustrated in Fig. 1, taken on the line 10 3—3 thereof, and

Fig. 4 is an enlarged sectional view of the structure illustrated in Fig. 1, taken on the line 4—4 thereof.

In the figures, I have illustrated a frame 5 15 having a window 6 mounted therein on a pair of vertically disposed trunnions 7 and 8. A regulating mechanism 9 is secured to the frame in engagement with the lower trunnion 8 for the purpose of swinging the window about the trunnions 7 and 8 to have portions of the window disposed forwardly and rearwardly of the aligned trunnions, move inwardly and outwardly of the frame.

Referring more particularly to Figs. 2, 3 and 4, the regulating device 9 comprises a pair of nested channel-shaped brackets 11 and 12 which form the housing for a worm 13 and a worm sector 14 which are mated therein. The bracket 12 has an extension on the bottom web which is flanged downwardly at 15 and reversely flanged at 16 parallel to the web portion of the bracket. The worm wheel sector 14 is disposed between the flange 16 and the web of the bracket 12. A shaft 17 is pivoted on the web of the bracket 30 12 and the flange 16 and passes through a hub 18 on the sector to which it is secured by a tapered pin or rivet 19.

The brackets 11 and 12 pivotally supports the worm 13 through the engagement of a split bearing element 24 with a bearing 21, disposed between collars 22 on the worm shaft. The split bearing is formed to have trunnions 25 on the ends which are disposed in aligned apertures in the webs of the brackets 11 and 12. In this 45 manner the worm 13 is mounted for pivotal movement on the trunnions 25 and for rotational movement through the engagement of the shaft portion 21 with the split bearing 24.

The opposite end of the worm is provided with 50 a shaft extension 26 which is engaged by a bearing segment 27 contained within a tube 28 which is supported on a side flange 29 of the bracket 11. A spring 31 biases the segment 27 toward the shaft to force the worm into intimate relation 55

with the worm wheel sector 14. A following plate 32 engages the opposite end of the spring which may be adjusted to any position in the tube 28 by a screw 33 to provide the proper amount of tension to the worm 13.

The side flanges of the brackets 11 and 12 are flanged outwardly at 34 and are mated with each other and permanently secured together by welding, brazing or a similar operation after the 10 worm and worm wheel have been mounted therein. The regulating unit thus formed, is a simple and compact device which is positive in operation and substantially fool proof. The web of the bracket 12 has a pressed out tongue portion 35 to 15 function as a stop to prevent the worm wheel sector from being moved out of contact with the worm.

The shaft 17 is provided with an enlarged shoulder 36 and a reduced extending portion 37 20 having a square recess extending therein. A portion of the side of the shoulder 36 is machined away, at 38 to a depth to communicate with the central opening. The machine portion 39 is spanned by a plate 39 secured to the shoulder 36 25 by screws 41. The plate 39 functions as a locking element to engage the square end of the trunnion 8 for securely clamping it in predetermined relation to the regulator. The outwardly directed flanges 34 of the regulator are provided with apertures 42 through which bolts, screws or suitable securing means 43 extend for the purpose of retaining the regulator on the frame 5.

The end of the shaft of the worm 13 beyond the bearing 21 is provided with a square end 44 35 to which an operating handle 45 is secured for operating the worm elements relative to each other and therefore the window 6, to move it to open or closed position.

It will thus be seen that the regulator is constructed from two outwardly presented channel elements which are nested together in spaced relation to provide a housing for the worm elements and a support for the unit which is rigid and positive. The worm is urged toward the worm 45 sector by a bearing segment operating on one end of the worm shaft while the other end thereof is mounted for pivotal movement. The driving element of the regulator is rigidly secured to the driven pivot of the window to positively position 50 the window and provide the lower pivot therefor.

While I have described and illustrated but a single embodiment of my invention, it will be ap-

parent to those skilled in the art that various changes, omissions, additions and substitutions may be made therein without departing from the spirit and scope of my invention as set forth in the accompanying claims.

I claim as my invention:

1. The combination with a frame and a window pivoted in the frame and having a trunnion, and a regulator engaging the trunnion for operating the window and comprising a channel bracket having outwardly extending flanges and a downwardly and reversely bent portion, a worm sector mounted between the reversely bent portion and the web of the channel, a shaft extending through the extending portion of the web and the worm sector and rigidly secured to the latter, a worm engageable with said sector, an element pivotally supporting the worm and having trunnion-like extensions, and a second bracket having outwardly extended flanges and greater depth than the first bracket and having nesting relation to the latter and pivotally engaging the trunnion extensions of said element.

2. The combination with a frame and a movable window in the frame, of a support, an elongated plate having portions at its ends secured to the support and a portion intermediate its ends which is bent laterally in a reverse manner to provide a flange substantially parallel to but spaced from the plate body, a second plate extending under the aforesaid flange and having offset ends secured to the support, and means journaled between the plate body, said flange and the second plate and operatively connected to the window for moving it.

3. The combination with a frame and a movable window in the frame, of a support, an elongated plate having portions at its ends secured to the support and a portion intermediate its ends which is bent laterally in a reverse manner to provide a flange substantially parallel to but spaced from the plate body, a second plate extending under the aforesaid flange and having offset ends secured to the support, a trunnion between the first plate body and flange and having its ends journaled in openings therein, a pin between the plates and having its ends supported in openings therein, a meshing worm wheel and worm respectively carried by the trunnion and pin, and means driven by the trunnion for moving the window.

ALBERT T. POTTER.
